US00D685266S

(12) **United States Design Patent**
Burleson, Jr. et al.

(10) **Patent No.:** **US D685,266 S**
(45) **Date of Patent:** **** Jul. 2, 2013**

(54) **CAN END**

(75) Inventors: **Lynn A. Burleson, Jr.**, Fort Dodge, IA (US); **John L. Phillips**, Monona, WI (US); **Donald M. Gust**, Oconomowoc, WI (US); **Rohm E. Bloedorn**, Delafield, WI (US)

(73) Assignee: **Silgan Containers LLC**, Woodland Hills, CA (US)

(**) Term: **14 Years**

(21) Appl. No.: **29/398,281**

(22) Filed: **Jul. 28, 2011**

(57) **CLAIM**

We claim the ornamental design for a can end, as shown and described.

DESCRIPTION

FIG. 1 is a perspective view of an embodiment of the claimed design;

FIG. 2 is a front view of the claimed design of FIG. 1, the rear view, the left side view and the right side view being the same as the front view;

FIG. 3 is a top view of the claimed design of FIG. 1;

FIG. 4 is a bottom view of the claimed design of FIG. 1; FIG. 5 is a sectional view taken along section line 5-5 in FIG. 3;

FIG. 6 is a perspective view of another embodiment of the claimed design;

FIG. 7 is a front view of the claimed design of FIG. 6, the rear view, the left side view and the right side view being the same as the front view;

FIG. 8 is a top view of the claimed design of FIG. 6;

FIG. 9 is a bottom view of the claimed design of FIG. 6; and, FIG. 10 is a sectional view taken along section line 10-10 in FIG. 8.

The broken lines in the drawings depict environmental subject matter only and form no part of the claimed design.

1 Claim, 6 Drawing Sheets
